UNITED STATES PATENT OFFICE.

JOHN W. BLÖDGETT, OF CHICAGO, ILLINOIS, ASSIGNOR TO THE N. TIRE COMPANY, OF CHICAGO, ILLINOIS, A CORPORATION OF ILLINOIS.

RUBBER BELT.

SPECIFICATION forming part of Letters Patent No. 761,054, dated May 24, 1904.

Application filed September 29, 1903. Serial No. 175,010. (No model.)

To all whom it may concern:

Be it known that I, JOHN W. BLÖDGETT, a citizen of the United States, residing at Chicago, in the county of Cook and State of Illinois, have invented certain new and useful Improvements in Rubber Belts, of which the following is a specification.

My invention relates to rubber belts for transmitting power, and is concerned with certain improvements in belts having their tread-surfaces or bearing-faces corrugated longitudinally or provided with longitudinal ribs or grooves.

The invention consists in the matters hereinafter described, and particularly pointed out in the appended claims.

In the accompanying drawings, which form a part of this specification and illustrate embodiments of my invention, Figure 1 is a cross-section of a completed belt made in accordance with my invention. Fig. 2 is a plan of a section of a strip of double-knit fabric which may be used in carrying my invention into effect. Fig. 3 is an end elevation of the fabric shown in Fig. 2. Fig. 4 is a view similar to Fig. 3 and showing a strip of single-knit fabric for the same purpose, and Fig. 5 is an end elevation of a tubular knit ribbed fabric which may be employed.

In producing belts embracing my invention I employ woven, braided, or knit fabric having longitudinal corrugations or provided with longitudinal ribs or grooves on one or both surfaces of the same. The fabric may be woven, braided, or knit from one or more threads and in any suitable manner to provide the corrugations or ribs and grooves referred to; but preferably I employ for this purpose a knit fabric made from a single thread which forms the warp and the woof and which is corrugated on both sides or faces. The fabric may be made as thick and strong as desired by using a thread of such size and strength as may be necessary therefor. The fabric may be made in either tubular form or in the form of a single strip, and in either of these forms it may be either double-knit, or with ribs and grooves on both faces, or single-knit, or with ribs and grooves on but one of its faces.

In practice I prefer to employ a one-piece longitudinally-corrugated fabric in the form of a strip—that is, not in tubular form—and double-knit from a single thread which forms the warp and the woof, the corrugations being provided on both sides or faces. Such a fabric is illustrated in Figs. 2 and 3 and is knit upon a machine by a backstitch, so that it presents a ribbed appearance or has corrugated faces or surfaces, this effect being produced by the longitudinal ribs *a*, which project slightly above the body of the fabric and provide the grooves or channels *b*. This one-piece fabric possesses the advantages that it may be made of any thickness and strength desired by using a coarse enough thread or twine, and being of only one thickness it cannot come to pieces. This fabric having the corrugated surfaces is coated with rubber-cement or a solution of raw rubber, which may be accomplished by dipping the fabric in a solution of raw rubber, or the solution may be applied by a brush or any other suitable means. The rubber-treated fabric is then allowed to dry a short time before putting the layers of rubber thereon to properly finish the surfaces. Only one such layer of rubber need be put on each side of the fabric if the layer is thick enough to friction and to cover the fabric, and one of such layers is preferably made wide enough to fold over the edges of the fabric, thereby covering the edges equally with the faces of the belt. If a sufficient amount of heavy rubber cement or solution is used on the belt, it will not be necessary to use the rubber layers. When the rubber has been applied in either of the methods above described, the belt as then prepared is put in a press and frictioned, the press being heated sufficiently to soften but not cure the rubber. In applying pressure to friction the belt thus formed I employ any suitable mold or former by which great pressure may be applied to the belt without permitting it to expand in any direction and which forces the rubber into the interstices and fibers of the fabric. After the rubber is frictioned it is put in a mold and cured, the mold being provided with corrugations coinciding with the corrugations in the fabric. The belt may

be made without using the frictioning-mold; but I prefer to use the frictioning-mold before curing the belt.

Instead of a fabric provided with corrugations or ribs and grooves on both surfaces I may employ a single-knit fabric or one having the corrugations or ribs and grooves on but one surface, as is shown in Fig. 4, the corrugated surface being that which is designed to run against the pulley when the belt is in use. In this form the corrugated effect of the fabric is produced by the ribs a' and grooves b' , formed only on one of the surfaces of the fabric. This fabric is treated in the same manner as the fabric heretofore described, the completed belt differing therefrom in that only one of the rubber surfaces of the belt is corrugated—that is to say, the surface on the face of the fabric having the ribs a' .

If the corrugated fabric used in making the belt is tubular, a rubber filling should be provided. This tubular fabric is knitted in such manner as to provide only its outer surface with ribs a' and grooves b' . The tubular fabric provided with its rubber filling or internal rubber lining is put in a frictioning-mold while in this state and subjected to pressure, whereby the rubber is forced into the interstices and the fibers of the fabric. After the tubular fabric is frictioned in a mold there may be as much raw rubber put on the opposite surfaces of the fabric as desired, after which it is cured, so that all the rubber and fabric will be pressed together so perfectly as to form a homogeneous body having upon its opposite surfaces corrugations which correspond to the corrugations in the fabric.

A belt constructed in this manner is strong and durable, and the fabric being of one piece and being thoroughly impregnated and filled with the rubber is proof against moisture, and for this reason the belt is not apt to disintegrate by reason of the agitation due to the wave produced in it when running over a pulley.

A decided advantage in the employment of a ribbed fabric resides in this, that with the

rubber forced into the fibers and interstices of the fabric and in the grooves when the rubber has worn off the face of the fabric there is still sufficient rubber in the fibers of the fabric and in the grooves to cause the belt to hang properly to the pulley. 50

The double-corrugated belt is pliable to adjust itself to the face of a crown-pulley, as the corrugations in its outer face allow it to bend transversely with less resistance than a solid belt. 55

This application is a continuation of an application filed by me November 5, 1901, Serial No. 81,192, which was a division of an earlier application filed by me July 15, 1901, Serial No. 68,388. 60

Having described my invention, what I claim is— 65

1. A belt consisting of a fabric having a longitudinally-corrugated surface and covered by and having its interstices filled with rubber, the rubber being corrugated to correspond 70 with the corrugations in the fabric.

2. A belt consisting of a fabric provided with longitudinal corrugations on both surfaces and covered by and having its interstices filled with rubber, the rubber being corrugated to correspond with the corrugations 75 in the fabric.

3. A belt consisting of a knit fabric provided with longitudinal corrugations and covered by and having its interstices filled with rubber, the rubber surfaces of the belt having corrugations coinciding with the corrugations 80 of the fabric.

4. A belt consisting of a knit fabric having corrugations on its faces and covered by and 85 having its interstices filled with rubber, the rubber faces of the belt having corrugations coinciding with the corrugations on the faces of the fabric.

In testimony whereof I affix my signature in 90 presence of two witnesses.

JOHN W. BLODGETT.
